[57] CLAIM

The ornamental design for an automotive steering lock body, substantially as shown and described.

DESCRIPTION

FIG. 1 is a perspective view of an automotive steering lock body showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a reduced perspective view thereof with the broken-line showing of the steering lock bar being for illustrative purposes only and forming no part of the claimed design.

FIG.1

FIG.2

FIG.3

FIG.4

FIG.5

FIG. 6

FIG. 7

FIG. 8
